United States Patent Office

Des. 219,079
Patented Oct. 27, 1970

219,079

LIST FINDER OR SIMILAR ARTICLE

Chuzo Mori, Tokyo, Japan, assignor to Carl Manufacturing Co., Ltd., Tokyo, Japan, a corporation of Japan

Filed July 22, 1969, Ser. No. 18,324

Term of patent 14 years

Int. Cl. D19—02

U.S. Cl. D74—1

FIG.1.

FIG.2.

FIG.3.

FIG.4.

FIG.5.

FIG.6.

FIG. 1 is a front perspective view of a list finder or similar article showing my new design.

FIG. 2 is a top plan view thereof.

FIG. 3 is a front elevational view thereof.

FIG. 4 is a right side elevational view thereof.

FIG. 5 is a rear elevational view thereof.

FIG. 6 is a bottom plan view thereof.

The left side of the list finder of this invention is similar to the right side.

I claim:

The ornamental design for a list finder or similar article, as shown and described.
